BOTTLE OUTLET CONTROL

Filed Sept. 1, 1928

FIG 1

Clifford E. Bown

INVENTOR

BY

C. A. Harpman

ATTORNEY

UNITED STATES PATENT OFFICE

CLIFFORD E. BOWN, OF YOUNGSTOWN, OHIO

BOTTLE-OUTLET CONTROL

Application filed September 1, 1928. Serial No. 303,593.

This invention relates to bottle outlet control. The principal object of this invention is to provide a stopper device for a bottle, arranged that an operator may control the outlet of fluid from the bottle as desired.

A still further object is to provide a means for more securely fastening the stopper within the mouth of a bottle. It is frequently necessary or desirable to control the outlet of fluid when pouring from a bottle. When pouring water into automobile batteries or the like, it often happens that the operator may find it more desirable to use one hand than two and at the same time have desired control over the volume of water to be released from the bottle. Again, it frequently is desirable in measuring medicine by drops to have an accurate control so that in place of using the ordinary dropper, the drops may be made by means of my improved device direct from the bottle.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

The invention is illustrated in the accompanying drawing, wherein:

Figure 1 is a side elevation of the device in proper position.

Figure 2 is a cross section taken on line 2-2 of Figure 1, showing a portion of the device that functions within the mouth of a bottle.

By referring to Figure 1, it will be seen that I have provided an ordinary bottle 1 provided with a neck portion 2. Within the mouth of the neck 2, I have provided an outlet control comprising a body member 3 which is made of suitable material, rubber being preferred. One side of the body member 3 is provided with a finger or thumb guard 4, while on the opposite side of the body member 3 there is provided a curved recess 5, the lower portion of said recess terminating in an

upper surface of a finger or thumb guard rest 6. The body member 3 is provided with two perpendicular openings for the reception of two tubes. Tube 7 is made of elastic material, preferably rubber, and is the outlet tube for the fluid that may be in the bottle. Tube 8 is a non-elastic tube, having an upper end 9 cut to conform to the curved recess 5 but projecting slightly above this curved recess.

By referring to Figure 2, it will be seen that the lower portion 10 of the body member 3 is provided with a plurality of peripheral saucer-shaped flanges 11. The object of these flanges 11 is to provide means for more securely holding the device within the mouth of the neck 2 of the bottle.

It will be obvious that as the device is pressed into proper position in reference to the bottle 1, it will be relatively easy to force the lower portion 10 into the mouth of the bottle as the flanges 11 are forced upwardly forming a resisting contact when an attempt is made to remove the device from the mouth of the bottle.

In operating the device, the bottle 1 which is provided with the fluid which is to be poured, is equipped with my device, by forcing the lower portion 10 into the mouth of the bottle. The bottle is now tipped by the operator who allows the contents of the bottle to escape through the tube 7 until the desired amount has been poured. At the same time, the operator presses his thumb or finger at point 12 on the flexible tube 7 so that the tube becomes flattened and closes the upper end 9 of the tube 8.

It will be noted that the tube 8 is smaller in diameter than the tube 7 so that when the fluid from the bottle 1 is being poured the weight of the fluid within the tube 7 overbalances the tendency of any fluid to escape through the tube 8 which functions as a vent tube.

What I claim is:

1. In a device of the class described, a body member, made of rubber, a lower end of said body member provided with a plurality of peripheral saucer-shaped flanges, finger or thumb guard formed on upper portion of

- said body member, a curved recess formed on opposite side from said finger or thumb guard, an elastic tube passing through said body member, a non-elastic tube passing through said device in a parallel position to said elastic tube, an upper end of said non-elastic tube projecting slightly above said curved recess, a finger or thumb guard rest formed on said body member, substantially as described.
- 5 2. In a device of the class described, a body member, a lower end of said body member provided with a plurality of peripheral saucer-shaped flanges, finger or thumb guard formed on upper portion of said body member, a curved recess formed on opposite side from said finger or thumb guard, an elastic tube passing through said body member, a non-elastic tube passing through said device in a parallel position to said elastic tube, an upper end of said non-elastic tube projecting slightly above said curved recess, a finger or thumb guard rest formed on said body member, substantially as described.
- 10 3. In a device of the class described, a body member, a non-elastic vent tube, functioning with said body member, an elastic outlet tube, functioning with said body member, said outlet tube positioned in close proximity to an upper end of said tube so that outlet tube is closed and at the same time closes vent tube by pressure on said outlet tube, substantially as described.
- 15 25 30

In testimony whereof I affix my signature.

35 CLIFFORD E. BOWN.
